WASTE PIPE CLEANING APPARATUS

Morris Rappaport, Brooklyn, N. Y.

Application May 16, 1939, Serial No. 273,829

1 Claim. (Cl. 15—104.30)

This invention relates to improvements in apparatus for cleaning waste pipes and the like and has for one of its objects the provision of an improved apparatus of simple and practical construction wherein the cleaning wire, commonly known as a "plumber's snake" may be conveniently and compactly stored preparatory to feeding the same into a pipe and for rotating said wire should it be found necessary to do so when passing through elbows or loosening obstructions in the pipe.

The above or other objects will appear more clearly from the following detailed description when taken in connection with the accompanying drawing which illustrates a preferred embodiment of the inventive idea.

In the drawing—

Figure 1 is a perspective view of the pipe cleaning apparatus constructed in accordance with the invention.

Figure 2 is a vertical longitudinal section therethrough taken on the line 2—2 of Figure 3, and

Figure 3 is an end elevation partly broken away and shown in section.

Referring more particularly to the accompanying drawing the apparatus is shown as comprising a supporting frame consisting of an elongated tubular bearing 4 which has bosses 5 extending from opposite sides thereof and adjacent its ends, and in which are secured the upper ends of the front and rear supporting legs 6 which maintain the apparatus in a substantially horizontal position when the same is resting upon a support.

Rotatably mounted in the bearing 4 and projecting beyond the ends thereof, is a sleeve member 7 on the forward end of which is secured a collar 8 which will abut the adjacent end of said bearing, and through which extends a set screw 9 utilized to clamp the flexible cleaning wire 10 in the sleeve 7 when it is desired to rotate said wire.

The rear end of the sleeve 7 has suitably secured thereto a conical housing generally indicated by the numeral 10a which is adapted to enclose the wire 10, and from which said wire is fed by hand through the inner open end of said sleeve 7 and from thence into a pipe to be cleaned. The housing 10a consists of the front and rear walls 11 and 12, the latter of which is provided with a central opening 13 of sufficient size to permit access to the interior of the housing to manipulate the wire if necessary. Upon

the front wall 11 adjacent the rear end of the sleeve 7, there is formed on said wall a series of spaced angular wire-binding elements 14 in the form of lugs which entered away from said wall 11 and which are concentrically arranged with respect to said sleeve. The wire, upon being fed outwardly from the casing and through the sleeve, will frictionally engage one of said elements 14 which will prevent kinking of the wire during a feeding operation, but such frictional engagement will not be sufficient to affect the free feeding of the wire. The engaged element 14 also acts to bind the wire and hold it stationary relative to the sleeve 7 and housing 10a when the latter two elements are rotated to, in turn, rotate the wire 10 should it become necessary to cause the forward end of the wire within the pipe to loosen an obstruction or force the same through a bend or elbow in the pipe. Should the binding action thus produced be insufficient, the set screw 9 may be tightened against the wire, as shown in Figure 2. To facilitate rotation of the sleeve 7 and housing 10a, the latter is provided on the exterior of its rear wall 12 and adjacent the periphery thereof with a bracket 15 to which is secured a handle 16 that may be grasped to rotate said elements 7 and 10a in a counter-clockwise direction, as viewed in Figure 3. The periphery of the housing 11 is provided at intervals with openings 17 which not only ventilate the housing, but also provide the means for securing the extremity of the wire 10 to said housing by passing said extremity through one of said openings as indicated at 18 in Figure 3. The wire 10 is coiled within the housing 10a in a single series of convolutions and after said wire has been withdrawn for a cleaning operation, the same will recoil within said housing, in the manner shown, when forced rearwardly through the sleeve 7.

What is claimed is:

A rotatable housing in which a pipe cleaning wire is adapted to be coiled and from which said wire is capable of being fed when cleaning a pipe, said housing having a wire outlet in one wall thereof, and a series of spaced wire-binding lugs arranged about and adjacent said outlet and extending in directions substantially away therefrom, said lugs being arranged and adapted to abut the wire to impart axial rotation thereto when said housing is rotated, but which the wire may clear when it is manually moved into and out of said housing.

MORRIS RAPPAPORT.
